UNITED STATES PATENT OFFICE.

CHARLES CLARENCE POOLE, OF EVANSTON, ILLINOIS, ASSIGNOR TO OLIVER TYPEWRITER COMPANY, OF CHICAGO, ILLINOIS, A CORPORATION OF ILLINOIS.

PAPER-MOVEMENT INDICATOR FOR TYPE-WRITERS.

No. 878,743.

Specification of Letters Patent.

Patented Feb. 11, 1908.

Application filed December 28, 1904. Serial No. 238,591.

To all whom it may concern:

Be it known that I, CHARLES CLARENCE POOLE, a citizen of the United States, of Evanston, in the county of Cook and State of Illinois, have invented certain new and useful Improvements in Paper-Movement Indicators for Type-Writers; and I do hereby declare that the following is a full, clear, and exact description thereof, reference being had 10 to the accompanying drawings, and to the letters of reference marked thereon, which form a part of this specification.

This invention relates to novel features of construction in the paper carriages of type-writing machines and more especially to an indicator adapted to indicate the extent to which the platen should be turned backward by hand for inserting new sheets, when making carbon copies of a number of writings on 20 a single record strip or sheet, and with uniform or predetermined spaces between such carbon copies.

The invention consists in the matters hereinafter described and more particularly pointed out in the appended claims.

In the accompanying drawings illustrating my invention:—Figure 1 is a perspective view of the right hand of a paper carriage, showing the platen therein and associated 30 parts. Fig. 2 is an end view of the paper carriage. Fig. 3 is an enlarged, sectional view of the parts constituting the invention, taken on a plane passing longitudinally through the axis of the platen shaft. Fig. 4 35 is a perspective view of a modified form of the indicating device. Fig. 5 is a sectional view thereof.

As shown in said drawings, A indicates the platen or paper roller, B the right hand end 40 plate of the paper carriage, in which the shaft *a* of the platen has bearing, C and D the paper guides on the carriage, E the upper longitudinal frame bar of the carriage, F one of the paper guides mounted on said frame 45 bar, G the upper guide roller of the carriage, and H the scale strip located above the platen adjacent to said guide roller. The platen shaft *a* has at its outer end a knob or disk A¹ by which the platen may be turned 50 by the hand of the operator. The parts above described correspond with those used at present in the type of machines known as the "Oliver" in which the type levers are located above the platen and the

types strike downwardly upon the top surface thereof.

I indicates an annular member or disk carrying an index finger or pointer J, and which is mounted on the platen shaft and is adapted to turn with said shaft and also to 60 be turned by hand on the shaft. Said disk or wheel is provided with circumferentially spaced graduations or scale marks, which are spaced at uniform angular distances apart to correspond with the line space movements of 65 the platen and are progressively numbered from the index hand or pointer J on the disk. K indicates an index finger or pointer on the carriage frame, which co-acts with the index finger J on the disk I, and L indicates an 70 index finger or pointer which is mounted on and turns with said disk I and is adapted to be turned or rotated about the shaft axis toward or from the index finger J, or placed in varying angular position with respect to 75 said finger J and to remain at any point to which it may be moved or adjusted.

So far as the general ends to be attained are concerned, the disk I may be engaged with the platen shaft by any form of device 80 adapted to hold the disk from freely turning on the shaft, so that the pointer J will turn or rotate with said shaft in the usual rotative or line spacing movement of the latter, while at the same time enabling said disk to be turned 85 or rotatively shifted on the shaft by hand when desired. Likewise, the pointer L may be connected with the disk I by any means adapted to retain the same in any position in which it may be placed with respect to the 90 pointer J on the disk, while enabling the said pointer to be readily shifted when desired. In the preferred embodiment of my invention illustrated in the drawings, the disk I is frictionally engaged with the shaft so that it 95 turns with the shaft but is adapted to be turned on the same while the pointer L is made adjustable on the disk and held in place thereon by an interlocking connection or by a locking device adapted to hold said 100 pointer in any position on the disk to which it may be moved.

Now referring to the details of construction in the features above referred to, illustrated in Figs. 1, 2 and 3 of the drawings: 105 The disk I is mounted on the platen shaft *a* outside of and adjacent to the end plate of the carriage frame. Attached to the said

platen shaft *a* inside of the disk *I* or between the same and the end plate of the frame is a disk *M*. The said disk *I* has on its outer face a central hub *I*¹ and is provided with a central, cylindric aperture to receive the shaft *a*, so that the said disk is adapted both to turn and slide endwise on the shaft. Said disk *I* is held in position adjacent to the fixed disk *M* by a sleeve or collar *O*, which is secured to shaft by a set-screw *o* and to which, in the particular construction illustrated in the drawings, the knob *A*¹ is rigidly attached and through the medium of which said knob is detachably secured to said platen shaft.

10 The disk *M* has a flat, outer, annular bearing face arranged opposite a like bearing face of the disk *I*, and between the movable and fixed disks *I* and *M*, is located an elastic or spring washer *N*, preferably having the form 15 of a circular, centrally apertured, thin plate of sheet metal, of elastic character, such as steel, which is slightly bent or curved laterally, as indicated in the drawings, (Fig. 3) so that it will be placed under tension when 20 confined between the fixed disk *M* and the rotative disk *I*, and will press or bear on the adjacent faces of said disks so as to afford frictional resistance to the turning of the disk *I* on the shaft.

25 The pointer *L*, which is mounted on and turns with the disk *I*, is, in the preferable construction illustrated in the drawings, attached to a radial arm *L*¹ secured to an annular member in the form of a hub or sleeve *L*² which is mounted and adapted to turn on the hub *I*¹ of said disk. The said sleeve *L*² is held from endwise movement on the hub by a ring *i* which surrounds the outer end of the hub and is secured by a screw *i*¹. Said 30 ring *i* is made larger in external diameter than the adjacent part of the sleeve or collar *O*, and is knurled or milled on its edge, so that it may be readily engaged by the fingers for turning the disk *I*. The locking device 35 for holding the pointer *L* adjustably in a desired position with respect to the pointer *J* on the disk *I*, consists, as shown in the drawings, of a spring actuated locking detent *P*, mounted on the arm and adapted to engage 40 one of a series of circumferentially arranged locking holes or recesses *Q* formed in the said disk *I*. Said locking detent *P* has the form of a sliding pin, mounted in a cylindric casing *l* on the arm *L*¹, and which is held normally in engagement with one of the locking 45 recesses *Q* by a coiled spring *l*¹ which surrounds the detent pin and is located in the casing *l*. Said spring bears at its one end against an inwardly facing annular shoulder 50 at the outer end of the casing and at its opposite end against a shoulder *p* on the said detent pin. Said detent *P* is provided at its outer end with a head or knob *p*¹ by which it 55 may be drawn outwardly by the fingers to release it from the recess *Q* with which it

engaged in the act of shifting or moving the pointer *L* relatively to the pointer *J*.

The indicating disk is preferably provided with a cylindric peripheral surface, on which are formed the graduations or scale marks referred to, so that the said graduations and the numbers applied thereto may be readily observed by the operator. In connection with the scale so marked on the disk *I*, the stationary pointer *K* is extended horizontally from the end plate of the carriage over the inner edge of the peripheral surface of the said disk and the pointer *L* extends at right angles from its supporting arm *L*¹ inwardly over said cylindric surface.

80 The operation of the indicating device described will be understood from the following:—The general purpose of the line space indicating device is to indicate to the operator the extent to which the platen must be turned backward when inserting a sheet of paper into the machine in order to bring the first line of printing the desired distance from the top margin of the paper, according to the space occupied by the heading on the sheet.

85 More particularly, the indicating device is designed for use in cases where it is desired to make out a number of bills or invoices and to make carbon copies of the same on a single strip or long sheet of paper.

90 In a case of this kind, it is desirable that the copies should be spaced as closely as possible on the record strip but at uniform distances apart, or with equal spaces between several records or

95 copies, and the line indicating device is employed to enable the operator to readily insert a new sheet for each separate original bill or invoice in such manner that the first

100 printed line of the carbon copy shall be located at a desired distance from the last printed line of the preceding carbon copy, while at the same time the first line of the original bill or invoice will come certainly in proper

105 position with respect to the top margin of the sheet in which the said original bill or invoice is printed.

110 As for instance, supposing the record strip and a sheet of paper for the original bill or invoice has been together inserted into the machine with carbon paper

115 between them, the first bill or invoice may be printed and the carbon copy will be made in the usual manner on the record strip.

120 The printing of the bill or invoice having been completed, the platen will then be turned to carry the original sheet out of the machine, and the platen then turned backwardly to move or shift the record strip backwardly to

125 such a point which when a new sheet is inserted, the part of the new sheet on which the first line is to be printed, will be located at such distance from the last line of the carbon copy as to leave a desired space on the record strip between the copies.

130 In using the indicating device described, the operator sets the pointer *L* at a distance

from the pointer J equal to the distance which it is necessary to turn the platen backward, after printing the last line of one bill or invoice, in order to start a new original sheet 5 into the machine in such manner that the first line of the next bill or invoice, when started at the proper place on the original sheet will, on the carbon copy sheet, come at a desired distance of two, three or more line 10 spaces from the last line of the preceding carbon copy. This may be done as follows: When the last line of the first bill or invoice has been completed the operator turns the disk I so as to bring the pointer J opposite 15 the fixed pointer K. He then turns the platen backward (the disk turning with the platen) until the platen reaches the proper position for the insertion of a new sheet, allowance being made for the desired space between 20 the first and the succeeding carbon copy. The platen being allowed to remain in this position, the pointer L is turned on the disk until it comes opposite the fixed pointer K. The angular distance between 25 the pointers J and L will then correspond with and indicate the distance which the platen must be turned backward after the printing of each original sheet, to bring the copy of the next like original sheet at the 30 desired distance from the copy of the preceding original sheet. In the use of the device in printing, after the pointer L has been adjusted to a fixed position relatively to the pointer J, in the manner described, or 35 otherwise, printing of each invoice is completed in the usual manner, and on completion of the last line thereof, the disk I is turned on the platen shaft, without turning the platen, until the said pointer J is opposite 40 the stationary pointer K. The platen is then turned forward, if necessary, to remove the printed original sheet, and then turned backward, carrying with it the disk I and pointers J and L until the pointer L is opposite the said stationary pointer K. The new sheet of paper is then inserted, by being thrust into the machine until its top edge is in contact with the first guide roller by which 45 it is gripped to the platen, and the platen 50 turned forwardly to carry the record sheet and the new original sheet into position for printing.

It follows that by the use of the device described, the operator, having once determined the angular distance or number of line spaces which the platen must be turned backwardly for starting a new sheet, can, in every instance, or when inserting each new original sheet for an original bill or invoice, 55 invariably turn the platen backward to the same distance, according to the angular distance between the pointers J and L and will thus be able to invariably bring the first printed line of the carbon copy the same distance from the last printed line of the pre-

viously made copy on said record sheet, thereby leaving uniform spaces between the several carbon copies of the record sheet. Moreover, the operator is able to locate the carbon copies on the record sheet as closely 70 together as desirable, without danger on the one hand of bringing the carbon copies together or overlapping them, and without liability on the other hand of separating the carbon copies on the record sheet so widely 75 as to waste space on the said record sheet.

The graduations or scale marks on the disk I are mainly useful to enable the pointer L to be set in desired positions for original sheets having headings of different widths, without 80 any tests to determine such positions, when the operator has previously ascertained and knows from recollection the places on the scale at which the pointer must be located for the different original sheets. Moreover, 85 as the graduations correspond with line spaces, if the operator desires to make the spaces between carbon copies greater or less, this can be done by merely shifting the pointer L backward or forward by one or 90 more spaces as desired.

If the graduations of the disk I were arranged reversely to that shown, or so as to run in the opposite direction from the pointer J, then on the completion of any bill or invoice the stationary pointer K, and the platen would then be turned backwardly far enough to bring the pointer J opposite the said stationary pointer. The result obtained will be manifestly the same in either case, it 95 being manifest that the angular distance between the pointers J and L will in any case correspond with the extent of backward turning movement required in the platen, and that it is immaterial whether the pointer J which is fixed to the disk or the pointer L which is adjustable therein be used to mark the starting point of the backward turning movement.

While the disk I is shown as having a projecting part forming the pointer J, yet the same result will be obtained by providing the said disk with a score line or zero mark for the scale. Moreover, the stationary pointer K may be replaced by a mark or score line on 105 the end plate of the carriage frame.

The graduations or scale marks on the disk are used merely for convenience in setting the pointer L relatively to the pointer J, or an equivalent mark on the disk I and has no 110 function to perform in the usual operation of the disk or wheel; the only parts coming into use at such time being the pointer K on the frame, and the fixed and adjustable pointers on the disk, the angular distance of which 115 latter from each other determines the distance through which the platen is to be turned backward in inserting each new sheet. In fact the disk I and its graduations may be omitted, in which case the pointer J or the 120

zero mark on the disk would be replaced by a pointer carried by a rotative arm on the platen shaft, and adapted to co-act with a like pointer carried by another arm having angular adjustment with respect to the first arm and adapted with said first arm to indicate the angular distance through which the platen is turned. A construction of this latter kind is shown in Figs. 4 and 5. In this instance, a flat disk or ring R surrounds the platen shaft adjacent to a disk S, affixed thereto, a spring washer s being located between said ring and disk. The ring R is attached to a sleeve R¹ on which is mounted a flat ring T which rests in contact with the ring R and is attached to a sleeve T¹. The rings R and T are provided with radial pointers R² T². The ring T is shown as held in frictional contact with the ring R by means of a spring ring or washer t surrounding the sleeve R¹ between the outer end of the sleeve T¹ and a ring r secured to the said sleeve R¹. The end plate of the carriage is, in this instance, provided with an arm or pointer V. The operation of the form of device shown in said Figs. 4 and 5 is the same as that of the form first described, the distance to which the platen is to be turned backward to give uniform spaces between the carbon copies, being determined by the angular distance apart of the relatively adjustable pointers R² and T² which are held from rotative movement when adjusted by the friction produced by the spring washer t.

From what has been heretofore stated, it will be understood that by the term "pointer", as used in the appended claims, is intended to mean as well a disk provided with an indicating mark or score line, or a part of or upon the carriage frame having such mark or score line, as a projecting part, arm or index finger, the part referred to in either case equally performing the functions of an indicating means to determine the line-space position of the platen or the extent to which it is turned.

I claim as my invention:—

1. The combination with a rotative platen, of two pointers which turn with and have rotative adjustment relatively to the platen and also have angular adjustment relatively to each other.

2. The combination with a carriage frame and rotative platen, of a pointer on the frame, and two pointers which turn with, and have rotative adjustment relatively to, the platen, and which also have angular adjustment relatively to each other.

3. The combination with a rotative platen and its shaft, of two pointers adapted for rotative movement on the shaft and with re-

spect to each other, means affording frictional engagement of one of said pointers with the shaft and means affording interlocking connection of the pointers with each other. 65

4. The combination with a rotative platen and its shaft, of a disk having rotative adjustment on the shaft, and two pointers carried by the disk and having angular adjustment relatively to each other. 70

5. The combination with a rotative platen and its shaft, of a disk having rotative frictional engagement with said shaft, and two pointers, one of which is fixed to the disk and the other of which has angular adjustment 75 on said disk and interlocking connection with the same.

6. The combination with a rotative platen and its shaft, of a disk having rotative adjustment on the shaft and provided with circumferential scale marks or graduations, and a pointer carried by and having angular adjustment on said disk. 80

7. The combination with a rotative platen and its shaft, of an annular member mounted 85 on the shaft, means affording frictional engagement of said annular member with the shaft, a second annular member mounted on the first named annular member, two pointers carried by said annular members, and means for locking the pointer on the second annular member to the first annular member in a desired angular relation to the other pointer. 90

8. The combination with a rotative platen 95 and its shaft, of a disk having a central hub and provided with a pointer, a sleeve mounted to turn on said hub and provided with a second pointer, means affording frictional engagement of the disk with the shaft and 100 means affording interlocking engagement of the second pointer with the said disk.

9. The combination with a rotative platen and its shaft, of a disk having a central hub, and provided with a pointer, a sleeve mounted 105 on said hub and provided with a second pointer, means for adjustably holding the disk from turning on the shaft, and locking means for holding the second pointer in a desired angular position relatively to the first pointer 110 embracing annularly arranged sockets in the said disk and a spring actuated detent on said second pointer adapted to engage either one of said sockets.

In testimony, that I claim the foregoing as 115 my invention I affix my signature in presence of two witnesses, this 22nd day of December, A. D. 1904.
